UNITED STATES PATENT OFFICE

2,221,777

TRACTION PRODUCING MEANS

Charles F. Chapman, Chicago, Ill.

Application December 24, 1937, Serial No. 181,629

9 Claims. (Cl. 291—23)

This invention relates to improvements in traction producing means and more particularly to means of the character indicated for employment on automobiles, both passenger cars and trucks.

5 The invention is also more specifically concerned with means of the character indicated whereby sand or other granular material is deposited in the path of travel of the vehicle.

The main objects of the invention are to provide 10 traction producing means which may be mounted within the rear portion or storage compartment of a vehicle so as to be protected from the weather and hidden from sight; to provide means of the character indicated whereby the sand or other material to be deposited may be effectively propelled forwardly and deposited in front of the driving wheels of the vehicle; to provide efficient and effective means for controlling the flow of the sand or other material 15 to the discharging device; to provide means which will expel the sand or other material with substantial force and which is of simple and durable construction, and efficient and effective in operation. Further objects of the invention are to provide 20 means for preventing the accumulation of sand in the discharge conduit of the device; to provide means whereby the operation of the device may be effected with great facility so as to interfere as little as possible with the driver's attention to traffic conditions; to provide a signal 25 means for informing the driver that the supply of sand for the device is low and should be replenished; and, in general, it is the object of the invention to provide an improved device of the character indicated.

This application is, in part, a continuation of my co-pending application Serial No. 100,120, filed September 10, 1936.

Other objects and advantages of the invention 40 will be understood by reference to the following specification and accompanying drawings (three sheets) wherein there is disclosed a device embodying a selected form of the invention, incorporated in a vehicle having a trunk on its rear end.

In the drawings:

Figure 1 is a side elevation.

Figure 2 is a rear elevation, certain parts being broken away to reveal other elements.

50 Figure 3 is a section on the line 3—3 of Figure 2. Figures 4, 5, 6 and 7 are sections respectively on the lines 4—4, 5—5, 6—6 and 7—7 of Figure 3, and

Figure 8 is a view of the device for controlling 55 the sand depositing means together with a dia-

grammatic representation of the sand depositing means and the electrical circuits employed for connecting the controlling means with the sand depositing means.

Figure 9 is a fragmentary view similar to a portion of Figure 7 but wherein certain portions have been removed to more clearly reveal the construction.

Referring now to the drawings, the improved mechanism herein contemplated is so designed 10 that the main mechanism thereof is adapted to be mounted in the vehicle within the rear end trunk or similar compartment. As shown in Figure 1, a sand hopper is represented at 10, a sand impeller or ejector at 11, and a sand discharge 15 or delivery pipe at 12. The delivery pipe 12 serves to carry the sand upwardly from the impeller 11 and to deposit it in the path of travel of the rear wheels of the vehicle.

As indicated in Figure 2, a pair of sand depositing devices are employed, one in connection with each of the two rear wheels. It will, of course, be understood that if preferred a single hopper could be employed and also that a single ejector could also be employed, in which case the 25 impeller should be of sufficient capacity to forcibly deliver sand into a pair of conduits suitably shaped to conduct and deliver the sand to the proper place in front of the driving wheels.

As shown in Figure 3, the hopper 10 is equipped 30 with an outlet 13 which connects with an ejector 14. The passage of sand or other material from the hopper to the ejector 14 is controlled by a sliding valve plate 15. The valve plate 15 is mounted on the outside face 16 of the receiving end of the ejector and between a pair of side guides 17—17 which may be formed integral with the receiving end of the ejector, or as shown in Figure 6, with a cover plate 18. The cover plate 18 is provided with an opening 19, the opening 40 being preferably of the shape of a trapezoid with its longest side located near the adjacent end of the sliding plate 15 when in closed position, as shown in Figure 3.

It has been found that the said shape of the 45 opening 19 is advantageous in connection with a valve used for controlling the flow of sand in that it facilitates the displacement of any particle of sand which would tend to lodge between the end of the valve plate and the side 50 edges and wide end of the discharge opening 19. I also prefer to employ the relatively long but narrow form of opening for the reason that the extent of movement required for the valve plate is small enough to be readily obtained by electro- 55

magnetic means which I prefer to employ for operating the valve.

The conduit 13 is equipped at its end with a flange 20 and suitable fastenings such as screws 5 as indicated in Figures 6 and 7 may be passed through said flange for attaching the end of the conduit 13 to the ejector 14.

The valve plate 15 may be controlled mechanically or electrically in various ways but I prefer to employ a solenoid 21 which has its plungers 22 connected to the valve plate 18 through the agency of a pin 23 which is carried and extends upwardly from the valve plate. It will be apparent from an inspection of Figure 3 that when the solenoid 21 is energized, the plunger element 22 thereof will move upwardly or inwardly of the electro-magnet and thereby slide the valve plate 15 upwardly so as to cause the free end 24 of the valve plate to be moved upwardly to a position adjacent the uppermost edge of the opening 19. To effect closing of the valves, a pair of springs 25-25 are connected between suitable fixed points such as indicated at 26 of the device and the ends of a cross arm 27 which is carried by 25 the valve plate 15.

The solenoid 21 comprises a core 66 of magnetic metal, for example, soft iron, an electric winding 67, and a plunger 22, also of suitable magnetic metal. The plunger 22 has its inner end portion 69 of tapered or frusto-conical shape as shown. The inner end portion of the core 66 is provided with a recess 70 of shape corresponding to the shape of the inner end of the plunger so that the latter may enter into the core as is apparent from an inspection of Fig. 3.

The described solenoid construction provides a relatively long plunger throw but a short air gap through which the lines of magnet force must flow in acting on the plunger. For example, the throw of the plunger is indicated at 71 and the air gap at 68, the latter being but slightly more than one-half the former. The shortness of the air gap greatly increases the starting pull of the solenoid, and the recessing of the core and entering of the plunger end thereinto, results in a cushioning of the movement of the plunger as it approaches its extreme, innermost position. To prevent metallic contact between the plunger and core, so as to insure return movement of the plunger without excessive spring strength, a non-magnetic insert button or pin 72 is provided in the bottom of the core recess 70.

The relationship of the air gap length to the plunger throw, may, of course, be varied by varying the angle of the tapered plunger end and the core recess. Hence the power of the solenoid may be made to suit the specific working conditions for which the solenoid is intended. The plunger may be recessed and the core tapered instead of as shown and other modifications and adaptations made of the indicated principle for increasing the starting pull of electro-magnetic devices.

The strength of the springs 25-25 is such that they will be effective to return the valve plate 15 to its closed position when the electric current to the solenoid magnet 21 is interrupted but not so long as the solenoid is energized. Means will presently be described for facilitating control of the circuit to the solenoid.

70 The ejector 14 comprises a substantially cylindrical recess 28 formed in an extension 29 of the housing 30 of an electric motor. The electric motor 30 is, of course, selected of suitable power and current consumption characteristics and the electric motor mechanism itself is separated from

the cylindrical chamber 28 by a wall 31 which may also be formed as an integral part of the motor housing. The opposite sides of the cylindrical valve 28 is closed by a suitable closure plate 32 which may be secured in place by means of screws or otherwise as preferred.

Within the ejector chamber 28 there is provided an impeller 33. The impeller 33 comprises a hub element 34 which is mounted on the end portions 35 of the electric motor shaft, said shaft 10 projecting into the ejector chamber 28 through an opening provided in the separating wall 31. The hub 34 carries a pair of oppositely disposed members 36 and 37, these members being U-shaped in form as best shown in Figure 6. They are each carried by a bracket element 38 which is flexibly or movably mounted on the hub element 34. In this instance the impeller member 36 is shown as being yieldably mounted on the hub through the agency of screws 39 and springs 40, the latter, yieldably supporting the bracket 38 of the impeller member 37, is shown as being flexibly or yieldably supported through the agency of a suitable rubber or other cushion 41 interposed between the bracket 38 and the adjacent face of the hub, screws 42 being employed to anchor the bracket to the hub. The heads of the screws 42 serve to determine the outermost position of the member 37 while the cushioned member 41 permits the bracket member 38 to be forced inwardly.

The yieldable mounting of the impeller members 36 and 37 as above described is a desirable feature in that it tends to prevent jamming and stopping of the rotation of the impeller by sand becoming wedged between the edges of the impeller elements 36 and 37 and the adjacent surface portions of the ejector member 28.

The ejector 14 is equipped with an outlet 43, also preferably formed integral with the motor housing and ejector housing as best shown in Figure 4. As shown in Figure 4, the outlet portion 43 is equipped with laterally extending ears 44-44 so located that their lower surfaces will engage or approach the top surface of the floor member 45 of the trunk or rear compartment in which the device is mounted.

In this instance the device is mounted so that the outlet portion 43 thereof rests on or engages a portion of the floor 45 which extends at an upward angle incident to the shaping of the floor member to provide suitable clearance thereunder for some of the running gear or associated mechanism of the automobile.

For conducting sand ejected or propelled by the ejector 14 forwardly and depositing the sand on the road or pavement in front of the driving wheels, there is provided a shaped conduit or pipe 46. The conduit 46 must, of course, be shaped to fit the particular vehicle to which the device is applied. In the case of certain vehicles made by one of the present day large manufacturers of automobiles, it has been found that the conduit 46 may be curved in such a way that it may at least partially enter the adjacent side frame member such as 48, of the vehicle chassis approximately at the top of the humped portion of said side frame which extends over the rear axle of the vehicle. The conduit may be positioned within the chassis side frame member as shown in Figure 5 for a considerable portion of its length so as to be protected by said side frame member from water and mud which may sometimes be splashed upwardly by the wheels of the vehicle. The conduit terminates in a downwardly ex-

tended curved portion 47 which has its end located in front of the adjacent rear wheel of the vehicle at a suitable elevation from the pavement. As shown in Figures 1 and 3, in some vehicles 5 the delivery conduit 46 would embody a portion which extends at an upwardly inclined angle or horizontally for such a length that the ejector may not in all cases be capable of throwing all 10 of the sand far enough to insure its downward travel by gravity in the downwardly inclined position of the conduit. In order to avoid the accumulation within the initial portion of the conduit of sand and consequent clogging of the conduit, the conduit in said horizontal or upwardly inclined portion may be provided with a multiplicity of openings 49 through which sand dropped to 15 the floor of said conduit portion would escape and fall to the pavement. To prevent the entrance of water splashed upwardly by the vehicle 20 into such apertured portion of the conduit, short tubes such as indicated at 50 may be provided for each of the openings 49, such tubes being effective to stop the travel of water before it reaches the interior of the conduit proper. To further guard 25 against the wetting of the interior of the conduit 46 by splashed-up water, a baffle plate 50a may be provided substantially as indicated in Figures 3 and 5.

The receiving end of the conduit 46 may be 30 secured in its operative position relative to the discharge or outlet portion 43 of the ejector by means of a suitable bracket or clamp member 51, designed to underlie the conduit and provided with ears or end portions 52—52 for receiving the 35 threaded ends of bolts or like fastenings 53—53 which extend through suitable openings in the ears 44—44 of said ejector outlet portion. The delivery end of the conduit 46 may be suitably supported by means of a bracket such as indicated at 54 secured to the running board or other conveniently located portion of the vehicle.

The operation of the device may be controlled 40 by a suitable switch or switches. Electrical switches and other controls for controlling the operation of various automobile accessories have 45 been more or less commonly mounted on the usual instrument board of the vehicle or on the steering wheel thereof and also on the floor adjacent the clutch and brake pedals. It has 50 occurred to me, however, that as a general rule, a device of the type herein contemplated would be actuated either before or after shifting gears. Therefore, in automobiles which are equipped 55 with a gear shift lever, I prefer to mount the switch for controlling the sand ejector on the gear shift lever adjacent the knob or other handle formation thereon so that when the operator of the vehicle grasps the gear shift lever he may 60 conveniently manipulate the switch to actuate the ejector without removing his hand from the gear shift lever.

As shown in Figure 8, a switch unit comprises 65 a housing 55 seated on the gear shift lever 56 near the upper end thereof and clamped in place thereon by means of a suitable clamping bracket indicated at 57. The housing 55 is provided with a more or less conventional push-button electric switch 58 which is connected in the electric circuit of the motor of each ejector. The wiring diagram forming a part of Figure 8 is of relatively 70 simple character and may be readily understood by those skilled in the art without detailed explanation.

It will be seen that an operator grasping the upper end of the gear shift ratchet 56 may easily 75 place his finger on the push-button 59 of the

switch 58 to close the circuit to the operating elements of the described device without removing his hand from the gear shift lever. This is a very desirable convenience which will be readily apparent when it is considered that the 5 requirement for the discharge of sand on the pavement arises only when the pavement is slippery frequently in emergencies when the vehicle begins to skid. Under such circumstances it is desirable that the operator be free to maintain 10 the operation of the sand ejecting device while also shifting gears to cause the vehicle to travel at a changed, usually lower, speed.

Because the device described is substantially concealed from view, it is desirable to provide 15 means for indicating to the operator of the vehicle the nearing exhaustion of his supply of sand in the hoppers 10. For this purpose there is provided in each of the hoppers, an arm 60 pivoted at one end as indicated at 61 to the side wall of 20 the hopper and provided adjacent its free end with a lightweight plate or board element 61 which will rest on top of the supply of sand in the hopper. The element 61 should be of light weight 25 so that it will not tend to sink into the sand. The 30 arm 60 carries a projecting pin 62 which is adapted to contact with one of the walls 63 of the sand hopper 10 when the supply of sand therein is lowered sufficiently to permit such engagement. The pin 62 is of metal and is mounted in the arm 35 60 (or in the member 61) so as to be insulated and it is connected by suitable flexible conductor to one terminal of a miniature lamp socket 64 which is mounted in the housing 55 on the gear shift lever. The other terminal of the electric 40 socket 64 is connected as shown in the wiring diagram to one terminal of the electric current, the other terminal of which is grounded in the metal of the vehicle. The sand hopper 10 is made of metal and is also grounded so it will be apparent 45 that when the contact pin 62 engages the wall 63 of the hopper, an electric circuit will be completed to energize a lamp 65 seated in the socket 64.

In the foregoing description reference has been 50 made more particularly to one sand delivering unit; however it will be understood that, as shown 55 in Figure 2, a separate unit for each of the rear wheels is considered preferable.

In the operation of the device, the impellers 36—37 are rotated in a clockwise direction as 60 viewed in Figure 3 and they tend to draw the sand upwardly in the outlet portion 43 and most of the sand so discharged appears to travel through the receiving end of the conduit 46 above the openings 49 therein. No substantial amount of sand is discharged through the openings 49 and the latter are provided merely as a safety measure to avoid a near possibility of clogging of the horizontally extending portion of the conduit. By this arrangement the elimination of a conduit extending more or less diagonally across the area of the wheels is permitted, and the positioning of a conduit in the more or less protected walls as 65 herein shown is facilitated without impairing operativeness of the device.

When the electric switch 58 is closed, both of the sand ejecting devices are simultaneously actuated and maintained in operation so long as the switch is maintained closed. As soon as the switch is permitted to open to break the circuit, the ejection of sand terminates since the valve plate 15 will be promptly closed by the action of the springs 25—25.

In the following claims reference to sand as 75

the material used in the apparatus described is intended to include any other form for material, for example, salt, which may be used in place of sand since it is obvious that the apparatus is not restricted to the handling of sand only. Changes in the described construction may be made without departing from the spirit of the invention, the scope of which should be determined by reference to the following claims, the same being construed as broadly as possible consistent with the state of the art.

I claim:

1. In apparatus of the character described, means for propelling sand comprising a housing having a substantially cylindrical chamber, a shaft entering said chamber, an impeller yieldably mounted on said shaft so as to be movable inwardly of the chamber, and means for rotating said shaft so as to cause said impeller to revolve in said chamber.
2. In apparatus of the class described, means for propelling sand or the like comprising a member having a cylindrical chamber therein, a shaft entering said chamber, a hub carried by said shaft, a pair of diametrically oppositely disposed impeller members respectively mounted on said hub so as to be movable inwardly and outwardly relative thereto, resilient means normally maintaining said impeller members in their outermost position, and means for rotating said shaft so as to cause said impeller to revolve in said chamber, the latter having an outlet opening for permitting the escape of sand from said chamber incident to the operation of said impeller.
3. In apparatus of the character described, the combination of means for forcibly propelling a stream of sand or the like, a conduit for conducting the propelled sand and having a discharge opening for delivering the sand to a predetermined location, said conduit having a generally horizontally extending portion, and an opening in said horizontally extending portion for bypassing said discharge opening so as to permit the escape from said horizontal portion of sand dropped from said propelled stream.
4. In apparatus of the character described, the combination of means for forcibly propelling a stream of sand or the like, a conduit for conducting the propelled sand and having a discharge opening for delivering the sand to a predetermined location, said conduit having a generally horizontally extending portion, an opening in said horizontally extending portion for bypassing said discharge opening so as to permit the escape from said horizontal portion of sand dropped from said propelled stream, and means for preventing the entrance of water into said horizontal conduit portion through said by-pass opening.
5. In combination in traction path sanding apparatus for an automobile, a sand container located rearwardly of the front of a wheel of the automobile, a chambered housing having a rotary impeller selectively operable therein, means for delivering sand to said housing from said container, and an outlet conduit extending a substantial distance forwardly in a generally horizontal direction and then downwardly to terminate in proximity to the front of said wheel, said conduit being adapted to convey sand ejected from said housing by said impeller, said impeller being formed and arranged to impart sufficient momentum to the sand to cause the latter to traverse the horizontal portion of said conduit and to be

forcibly delivered to the traction path of said wheel.

6. In combination in a traction path sanding apparatus for automotive vehicles, a housing having an annular chamber of substantial diameter constructed and arranged to be mounted with the axis thereof substantially horizontal, means for supplying sand by gravity to said chamber, said means including an inlet conduit arranged to deliver sand to the lower annular wall portion of 10 said chamber, an outlet conduit from said chamber located on the opposite side of said chamber from said inlet, a rotary impeller mounted in said chamber and having a plurality of sand engaging blades, means for rotating said impeller in one 15 direction at a high speed to carry said blades successively past said inlet and across said lower wall portion to sweep the sand therefrom into said outlet conduit, said blades and the points of communication of said inlet and outlet conduits with 20 the chamber being spaced circumferentially a sufficient distance and so arranged relative to each other as to permit substantial completion of the sand ejecting operation of one blade before a succeeding blade engages a new supply of sand 25 delivered to said chamber by said inlet conduit, and means for directing the ejected sand into the traction path of a vehicle wheel.

7. In combination in a sanding device of the class described, a sand receptacle having an outlet, sand impelling means, means for delivering sand from said receptacle to said impelling means, a duct having one end connected to said impelling means and extending a substantial distance in a generally horizontal direction 30 therefrom and then downwardly and provided with a discharge opening to deliver sand discharged by said impelling means into the traction path of a wheel of a vehicle on which the sanding device is adapted to be mounted, said impelling device being normally operable to throw the sand through the length of said horizontally extending duct part, and said horizontally extending duct part being provided with an opening for bypassing said discharge opening 35 to permit the escape of sand which may have been insufficiently impelled to travel entirely through said horizontally extending part, thereby to maintain said part in clear condition for the free passage of impelled sand.

8. In combination in a sanding device of the class described, a sand receptacle having an outlet, sand impelling means, means for delivering sand from said receptacle to said impelling means, a duct having one end connected to said impelling means and extending a substantial distance in a generally horizontal direction 40 therefrom and then downwardly and provided with a discharge opening to deliver sand discharged by said impelling means into the traction path of a wheel of a vehicle on which the sanding device is adapted to be mounted, said impelling device being normally operable to throw the sand through the length of said horizontally extending duct part, and said horizontally extending duct part being provided with an opening for bypassing said discharge opening 45 to permit the escape of sand which may have been insufficiently impelled to travel entirely through said horizontally extending part, and a tube communicating with said horizontally extending duct part through said by-pass opening and depending therefrom at an angle which is conducive to the gravitation of sand through 50 said tube, said tube serving to prevent water 55 from entering said tube.

splashed upwardly by the wheel of the vehicle from reaching the interior of said horizontally extending duct part, whereby the latter is maintained in clear condition for the free passage of impelled sand.

5. In apparatus of the class described, the combination of means for propelling sand, a receptacle for containing a supply of said material, a conduit for conducting said material from

said receptacle to said propelling means, and valve means for closing said conduit and comprising a slidable plate element, said conduit being of trapezoidal shape adjacent said slidable valve plate and the latter being movable transversely of the parallel sides of said trapezoidal shaped conduit portion and toward the longest side thereof for closing said conduit.

CHARLES F. CHAPMAN.
